UNITED STATES PATENT OFFICE.

JAMES THORNTON, OF WELLSVILLE, ASSIGNOR OF ONE-FOURTH HIS RIGHT
TO PRATT & LETCHWORTH, OF BUFFALO, NEW YORK.

IMPROVEMENT IN HAMES.

Specification forming part of Letters Patent No. **170,209**, dated November 23, 1875; application filed
October 12, 1875.

CASE B.

To all whom it may concern:

Be it known that I, JAMES THORNTON, of Wellsville, in the county of Allegany and State of New York, have invented a certain Improvement in Hames, which improvement is fully set forth in the following specification, reference being had to the accompanying drawing.

My invention relates more particularly to that kind of hames which are provided near the top with a corrugated strip or plate, to which the loop to which the upper hame-strap is attached is adjustably connected; and it relates to an improved manner of securing the corrugated plate to the hame.

In the accompanying drawing, Figure 1 is a side elevation, Fig. 2 a vertical section, and Fig. 3 a front elevation, of the top portion of a hame provided with my improvements. Fig. 4 is a cross-section in line $\alpha\alpha$, Fig. 2. Fig. 5 is a detached view of the corrugated plate in a slightly-modified form.

Like letters of reference designate like parts in each of the figures.

A represents the wooden portion of a hame made in the usual form, and B the metallic back-strap. C is the corrugated metallic plate to which the loop D of the hame-strap is adjustably connected. The inner edge of the plate C is make tapering or wedge-shaped in cross-section, as clearly shown in Fig. 4, so

as to be readily driven into the wood, while its outer edge is provided with a series of notches or corrugations, e, in which the loop D is engaged. The back-strap B is provided on the front side of the hame with a narrow slot, b, corresponding in size with the length and thickness of the plate C, so as to allow the latter to be readily driven into the wood, while at the same time retaining the plate against lateral displacement.

If preferred, the inner wedge-shaped edge of the plate C may be provided with one or more pointed prongs, e, for better securing it in the wooden portion of the hame.

The plate C, constructed as above described, is very cheaply manufactured, while presenting a pleasing appearance, and is readily and securely attached to the hame at a small expense.

I claim as my invention—

The combination, with the hame and back-strap B, provided with slot b, of the plate C, having its outer edge corrugated, and its inner edge tapering or wedge-shaped, substantially as and for the purpose hereinbefore set forth.

JAMES THORNTON.
